UNITED STATES PATENT OFFICE.

CHARLES B. TAYLOR, OF MILWAUKEE, WISCONSIN, ASSIGNOR TO ALLIS-CHALMERS
MANUFACTURING COMPANY, OF MILWAUKEE, WISCONSIN, A CORPORATION OF
DELAWARE.

PRIME-MOVER CONTROL SYSTEM.

Application filed December 13, 1926. Serial No. 154,386.

This invention relates to prime mover control systems. It is particularly adapted for prime movers which it is desired to start automatically.

- 5 A prime mover usually has a comparatively large starting resistance, that is, more operating fluid must be admitted to start it from rest than may be necessary to bring it to a predetermined speed after it is once 10 started. This necessitates first admitting a comparatively large quantity of operating fluid, then reducing the amount and then again increasing it. It is an object of this 15 invention to provide means whereby these results may be accomplished automatically, and, more particularly, in a simple and efficient manner.

A more specific object is the provision of a control system for accomplishing the hereinbefore mentioned objects in which the prime mover is also controlled by means of a speed governor.

A further more specific object is the provision of a control system for accomplishing the hereinbefore mentioned objects in which a fluid pressure operated servo-motor is utilized for controlling the admission of operating fluid to the prime mover. Other objects will appear hereinafter as the description of the invention proceeds.

The novel features of the invention will appear from this specification and the accompanying drawing forming a part thereof and illustrating one embodiment of the invention and all these novel features are intended to be pointed out in the claims.

The single figure of the drawing is a diagrammatic representation showing how the invention may be applied in the control of a hydraulic turbine.

Referring to the drawing, the prime mover which is to be controlled is here shown as a hydraulic turbine 1 which is adapted to drive a generator 2. The generator 2 may feed a line or distribution system 3 when a circuit breaker 4 is closed. The circuit breaker 4 may be provided with an operating magnet 5 which may be energized in any suitable manner. The circuit breaker 4 is here also shown as provided with a normally closed auxiliary contact 6 for a purpose to be hereinafter set forth.

The supply of water to the turbine 1 may be controlled by any suitable means such as

the gate 7. It is of course understood that the supply of operating fluid to the prime mover may be controlled in any usual manner as by valves, guide vanes etc. Hereinafter the term gate will be used for the sake of brevity to designate any means for controlling the admission of operating fluid to the prime mover. The gate 7 may be operated by any suitable means as for example a servo-motor 8 having its operating piston connected through a crank 9 to the gate 7. Fluid under pressure may be admitted selectively to the servo-motor to cause it to move in one direction or the other by means of a regulating valve 10 supplied by fluid under pressure through a pipe 11. The regulating valve is operated by means of a valve stem 12 suitably connected to a pivot 13 at one end of the floating lever 14. The connection between the regulating valve and floating lever is here shown as including a spring cage 15 and a spring 16.

In the position of the parts as shown a control finger 17 pivoted at 18 is adapted to hold the regulating valve 10 in its illustrated position by engagement with a projection 54 associated directly or indirectly with the valve stem 12. In this position of the regulating valve fluid under pressure from pipe 11 is admitted by the regulating valve to the servo-motor so that the gate 7 may be moved to the closed position.

A rod 19 is operatively associated with the control finger 17 by means of a pin and slot connection 21. The rod 19 may be biased so as to in turn bias the control finger 17 in a clockwise direction, by means of a spring 20. The rod 19 may be moved against the bias of spring 20 by means of a core and magnet 22, 23. Any suitable means such as a dash pot 24 may be utilized to retard the motion of the control finger 17. Any other suitable means for operating control finger 17 may be utilized.

The floating lever 14 is controlled by means of fly balls 25, which may be suitably driven in response to the speed of the prime mover, as for example by means of a belt 26. The fly balls are connected to the floating lever at a floating pivot 27. Another end of the floating lever 14 is provided with a pivoted nut 28 adapted to receive a screw 29. The screw 29 is for the usual purpose of adjusting the relative position of the nut

28 and a shaft 30 which is associated with the screw 29. The shaft or rod 30 is associated with one element of a dash pot or compensating device 31, the other element 5 of which is operatively related to the gate 7 as by means of a bell crank 32, a link 33 and an arm 34 movable in unison with the gate 7.

A switch 37, 38 is here shown as held in 10 the closed position by means of an extension on the arm 34 which engages the projection 35 adjustable on an operating rod 36 for the switch 37, 38. The switch rod 36 may be biased toward the other position by means 15 of a spring 39. The bias of spring 39 may also be overcome by means of a core and coil 40, 41 associated with the switch rod 36.

The prime mover is provided with means 20 responsive to a predetermined degree of rotation thereof, here shown as including a centrifugally responsive device 42 which when a predetermined degree of rotation occurs is adapted to actuate switches 43, 44.

Any suitable source of current 48 may be 25 provided for operating the control circuits. A master control switch 45 for the control circuits is here shown, and this switch may be located at any desired place. When the control switch 45 is closed, a pair of control 30 buses 46, 47 is energized.

The electrical connections of the control 35 system will be best understood by a description of the operation of the system as a whole. In the following description relays will be referred to by their operating coils.

The operation is as follows. Upon energization of the control buses 46, 47 by closure of switch 45 a relay 49 is energized from bus 46 through the normally closed or back contacts and a movable member 50 of a relay 51, from thence through coil of relay 49 to bus 47. Energization of relay 49 closes a contact 52 thereof thereby energizing magnet or coil 23 from buses 46, 47 as is clear. 40 This causes a counter-clockwise movement at a predetermined rate of control finger 17. The projection 54, and consequently the valve stem 12, follows this movement of control finger 17 under the influence of 45 spring 16 thereby first moving the regulating valve 10 to the neutral position and then to a position in which fluid is admitted to the servo-motor 8 so that the gate 7 is moved toward the open position. When sufficient water is admitted to the turbine 1 to cause it to start from rest the gate 7 is ordinarily opened considerably further than is necessary to bring the prime mover up to normal speed and maintain it at that speed. 55

60 When the prime mover has attained a predetermined degree of rotation the device 42 will effectively operate switches 43, 44. It will be noted that the closure of switch 43 will not complete any circuit through coil 41 65 for the reason that as the gate 7 opened the

spring 39 pulled the switch rod 36 toward the left as viewed in the drawing, being permitted to do so by reason of the counter-clockwise movement of arm 34. The closure of contact 44, however, completes a circuit 70 for a relay 51, from bus 46 through a resistance 53, through auxiliary contact 6, through coil 51 through contact 44 to bus 47.

Relay 51 is consequently energized opening its back contacts and closing its front or upper contacts. It will be noted that the front contacts of relay 51 serve to bypass contact 44 and consequently relay 51 is maintained energized. The opening of the back contacts of relay 51 deenergizes relay 49 which 75

consequently moves the control finger 17 in a clockwise direction thereby returning the regulating valve 10 to the position shown in the drawing and causing the servo-motor to 80 reclose the gate 7. Reclosure of the gate 7 causes the switch rod 36 to again assume the position shown in the drawing. Inasmuch as the switch 43 is now closed and contact 38 is also closed, a circuit is completed for 85 the coil 41 which acts upon core 40. The closure of switch 37 is adapted to short circuit the coil of relay 51 thereby deenergizing that relay. It is of course obvious that the relay 51 may be deenergized in some 90 other manner than by short circuiting the same. The deenergization of relay 51 causes that relay to reclose its back contacts thereby again energizing relay 49 and consequently 95 also coil 23. The control finger 17 is therefore again moved in a counter-clockwise direction to thereby, as previously described, move the gate 7 toward the open position. Inasmuch as coil 41 is now energized, the 100 switches 37, 38 will be maintained in the closed position even though arm 34 moves away from projection 35.

Meanwhile the prime mover has been increasing in speed and at a predetermined speed the fly balls 25 assume control of the regulating valve 10, the control finger 17 having moved out of the way of the projection 54 thereby permitting full control by means of the fly balls. As the gate 7 opens the bell crank 32 is rotated in a clockwise direction to provide compensating movement through dash pot 31 acting on nut 28 to rotate the floating lever 14 about its floating pivot 27 in the well known manner to readjust the regulating valve 10. When the prime mover has attained a speed which corresponds in frequency to the frequency of line 3, the coil 5 may be energized in any suitable manner to close circuit breaker 4, the generator 2 then supplying energy to 115 line 3. The closure of circuit breaker 4 opens auxiliary contact 6 thereby avoiding any waste of current in resistance 53.

It should be understood that it is not desired to limit the invention to the exact de- 120

tails of description shown and described for obvious modifications may occur to persons skilled in the art.

It is claimed and desired to secure by Letters Patent:

1. In a control system for a prime mover having a gate for admitting operating fluid thereto, means for operating said gate, means for controlling said operating means to cause said gate to open a predetermined amount, means responsive to a predetermined degree of rotation of said prime mover for causing said controlling means to effect movement of said gate toward closed position a predetermined amount, and means effective when said gate has been moved said predetermined amount for causing said controlling means to effect movement of said gate toward open position.
2. In a control system for a prime mover having a gate for admitting operating fluid thereto, a servo-motor for operating said gate, a regulating valve for said servo-motor, means for causing said regulating valve to move to gate-open position to thereby open said gate and start said prime mover from rest, means responsive to a predetermined degree of rotation of said prime mover for causing said regulating valve to move to the gate-closed position, and means effective when said gate has been moved a predetermined amount toward closed position for causing said regulating valve to move to the gate-open position to thereby reopen said gate.
3. In a control system for a prime mover having a gate for admitting operating fluid thereto, operating means for said gate, means including a magnet for controlling said operating means, means for initially energizing said magnet to cause said operating means to open said gate, means responsive to a predetermined degree of rotation of said prime mover for deenergizing said magnet to thereby cause closing movement of said gate, means responsive to the predetermined closing movement of said gate for reenergizing said magnet to thereby reopen said gate, and means for maintaining said magnet energized after said gate reopens.
4. In a control system for a prime mover having a gate for admitting operating fluid thereto, a servo-motor for operating said gate, a regulating valve for said servo-motor, means including a magnet for causing said regulating valve to move to gate-open position to thereby open said gate and start said prime mover from rest, means responsive to a predetermined degree of rotation of said prime mover for deenergizing said magnet to thereby cause closing movement of said gate, means responsive to a predetermined closing movement of said gate for reenergizing said magnet to thereby reopen said gate, and means for maintaining said gate open.
5. In a control system for a prime mover having a gate for admitting operating fluid thereto, operating means for said gate, means including a magnet for controlling said operating means, means for initially energizing said magnet to cause said operating means to open said gate, means responsive to a predetermined degree of rotation of said prime mover for deenergizing said magnet to thereby cause closing movement of said gate, means including a switch responding to a predetermined closing movement of said gate for reenergizing said magnet to thereby reopen said gate, and means responsive to the closure of said switch for maintaining said switch closed after said gate reopens.
6. In a control system for a prime mover having a gate for admitting operating fluid thereto, operating means for said gate, means including a magnet for controlling said operating means, means for initially energizing said magnet to cause said operating means to open said gate, means responsive to a predetermined degree of rotation of said prime mover for deenergizing said magnet to thereby cause closing movement of said gate, means responsive to the predetermined closing movement of said gate for reenergizing said magnet to thereby reopen said gate, means for maintaining said magnet energized after said gate reopens, and a governor responsive to the speed of said prime mover for controlling said gate-operating controlling means.
7. In a control system for a prime mover having a gate for admitting operating fluid thereto, operating means for said gate, means for controlling said operating means, means including a magnet which when energized or deenergized respectively causes said controlling means to effect opening or closing movement respectively of said gate, a relay for controlling said magnet, means for initially energizing said relay, a second relay having a contact in the circuit of said first relay, means responsive to a predetermined amount of rotation of said prime mover for energizing said second relay, means for maintaining said second relay energized in response to the operation thereof, switch means, means operatively related to said gate for actuating said switch means as said gate moves out of and into a predetermined closed position, means whereby actuation of said switch means in response to closing movement of said gate deenergizes said second relay, and means for maintaining said switch means closed in response to actuation thereof.
8. In a control system for a prime mover having a gate for admitting operating fluid thereto, means for operating said gate, means for controlling said operating means,

means for initially causing said controlling amount, means responsive to a predetermined degree of rotation of said prime mover for causing said controlling means to effect movement of said gate toward closed position to a predetermined amount, means effective when said gate has been moved said predetermined amount for causing said controlling means to effect movement of said gate toward open position, and a governor responsive to the speed of said prime mover for controlling said gate-operating controlling means.

9. In a control system for a prime mover having a gate for admitting operating fluid thereto, means for operating said gate, means for controlling said operating means jointly responsive to said gate-responsive means and said rotation-responsive means for controlling said gate-responsive means.

10. In a control system for a prime mover having a gate for admitting operating fluid thereto, means for operating said gate, means for controlling said operating means jointly responsive to said gate-responsive means and said rotation-responsive means for controlling said gate-responsive means.

11. In a control system for a prime mover having a gate for admitting operating fluid thereto, means for operating said gate, means for controlling said operating means jointly responsive to said gate-responsive means and said rotation-responsive means for controlling said gate-responsive means.

12. In a control system for a prime mover having a gate for admitting operating fluid thereto, means for operating said gate, means for controlling said operating means jointly responsive to said gate-responsive means and said rotation-responsive means for controlling said gate-responsive means.

13. In a control system for a prime mover having a gate for admitting operating fluid thereto, means for operating said gate, means for controlling said operating means jointly responsive to said gate-responsive means and said rotation-responsive means for controlling said gate-responsive means.

14. In a control system for a prime mover having a gate for admitting operating fluid thereto, means for operating said gate, means for controlling said operating means jointly responsive to said gate-responsive means and said rotation-responsive means for controlling said gate-responsive means.

15. In a control system for a prime mover having a gate for admitting operating fluid thereto, means for operating said gate, means for controlling said operating means jointly responsive to said gate-responsive means and said rotation-responsive means for controlling said gate-responsive means.

16. In a control system for a prime mover having a gate for admitting operating fluid thereto, means for operating said gate, means for controlling said operating means jointly responsive to said gate-responsive means and said rotation-responsive means for controlling said gate-responsive means.

In testimony whereof, the signature of the inventor is affixed hereto.

CHARLES B. TAYLOR.
